CLAIM

The ornamental design for a wine cork puller, as shown and described.

DESCRIPTION

FIG. 1 is a left side, front and top, isometric view of a wine cork puller showing my new design;

FIG. 2 is a top plan view thereof;

FIG. 3 is a front, elevational view thereof;

FIG. 4 is a right side elevational view thereof;

FIG. 5 is a rear elevational view thereof;

FIG. 6 is a bottom plan view thereof; and,

FIG. 7 is a left side elevational view thereof, showing my new design in an extended orientation.
